US00D879835S

(12) **United States Design Patent** (10) **Patent No.:** **US D879,835 S**
Höhne et al. (45) **Date of Patent:** **** Mar. 31, 2020**

(54) **DISPLAY SCREEN OR PORTION THEREOF
WITH SET OF ICONS**

(71) Applicant: **Apple Inc.**, Cupertino, CA (US)

(72) Inventors: **Sascha Höhne**, Hamburg (DE); **Ole Lagemann**, Hamburg (DE)

(73) Assignee: **Apple Inc.**, Cupertino, CA (US)

(**) Term: **15 Years**

(21) Appl. No.: **29/700,168**

(22) Filed: **Jul. 31, 2019**

Related U.S. Application Data

(63) Continuation of application No. 29/659,780, filed on Aug. 13, 2018, now Pat. No. Des. 859,467, which is a continuation of application No. 29/594,876, filed on Feb. 23, 2017, now Pat. No. Des. 828,855, which is a continuation of application No. 29/552,022, filed on Jan. 19, 2016, now Pat. No. Des. 782,516.

(57) **CLAIM**

The ornamental design for a display screen or portion thereof with set of icons, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE shows a display screen or portion thereof with set of icons showing our new design.

The peripheral dashed broken lines illustrate a display screen or portion thereof and form no part of the claimed design.
